SHIPPING CONTAINER

Orva O. Nickerson, Fort Wayne, Ind., assignor to
 Fort Wayne Corrugated Paper Company, Fort
 Wayne, Ind., a corporation of Indiana

Application October 5, 1936, Serial No. 103,983

1 Claim. (Cl. 229—33)

My invention relates to improvements in shipping containers or packaging cases of the type primarily formed of fiber board or corrugated fiber board.

5 It is one of the objects of my invention to provide a shipping container which will have extreme rigidity, particularly when formed of fiber board, and which may be formed from a single blank of material. Such construction materially 10 reduces the cost of production not only in the formation of the blank into a container but also in the cutting of the blank.

Furthermore, by forming the container from a single blank of material, greater rigidity and 15 strength is given to the entire structure.

For the purpose of disclosing my invention, I have illustrated an embodiment thereof in the accompanying drawing, in which:

Fig. 1 is an end elevation of a container embodying my invention;

Fig. 2 is a transverse sectional view thereof;

Fig. 3 is a sectional view of the end wall;

Fig. 4 is a plan view of the blank;

Fig. 5 is a bottom plan of one of the cover 25 corners; and

Fig. 6 is a perspective view showing particularly the intermediate breaks.

The case is made of an integral sheet of fiber board, corrugated fiber board or other suitable 30 material and is formed from a single blank like that illustrated in Fig. 4. This blank is provided adjacent its longer ends with a pair of crease lines 1 and at right-angles thereto are provided a pair of crease lines 2 and a second pair of crease 35 lines 3. A third pair of crease lines 4 is made at the opposite ends of the body blank. On continuations of the pair of crease lines 2 and beyond the crease lines 1, the body is slit on its opposite sides as at 5—5 and 6—6. The body 40 is also slit on each side for a short distance along the pair of crease lines 3—3 as at 7—7 and 8—8. These slits meet pairs of slits 9—9 and 10—10 parallel with the crease lines 1—1 and extending beyond, toward the opposite ends of the 45 blank, the crease lines 3—3. The ends of the blank are slit as at 11—11 and 12—12 on lines continuing the crease lines 1—1 and a pair of recess cuts on each edge such as 13—13 and 14—14 are formed for a purpose which will more 50 fully hereinafter appear. In addition to the above crease lines and slits, openings 15—15 are formed in the body and indent openings 16—16 and 17—17 are formed in each edge.

The above creasing and slitting provides a 55 blank containing a bottom portion 18, two end

walls 19, two side walls 20 and two cover members 21. Each of the cover members is provided with a side flap 22 and two end flaps 23. Furthermore, the two side walls are each provided at their opposite ends with a reinforcing flap 24 5 and a second reinforcing flap 25.

In folding the blank, the two side walls 20—20 are folded upwardly along the crease lines 2—2. The end flaps 24 of each side wall are then folded inwardly and the flaps 25 are folded downwardly 10 upon the inwardly turned flaps 24. The end walls 19 are then folded upwardly against the inturned flaps 24 and these parts all suitably stitched together by metallic stitching, metallic staples or other securing members. 15

The side flaps 22 on the cover members 21 are folded inwardly and the end flaps 23 likewise folded inwardly with the portions 26 of the end flaps bent to overlap the side flaps. These overlapping portions are likewise stitched together, 20 the covers being adapted to hinge on the crease lines 3—3. It will be noted that each cover 21—21 is only half the width of the box and that when the parts are assembled, as above described, the recesses 13—13 and 14—14 form 25 downwardly extending slots in the upper edge of the side walls to receive the downturned edge flaps 22 of the cover with the end flaps 23 overlapping the outside of the ends. It will also be noted that the openings 15—15 form hand holds 30 in the end walls of the cover and that the adjacent edges of the flaps 25 abut one another to form a reinforcement at the bottom of the slots 13 and above the hand hold openings. 35

These slots 13—13 in the end walls of the case 35 are equal to the combined width of the side flaps 22 together with the turned tongues 26 of the cover members so that when the cover members are closed, the downturned edges thereof will readily take into the slots in the end walls. 40

In order to support the cover members 21 when folded into closed position and in order to also divide the box into two compartments, I provide a divider 27 having angularly turned flaps 28 lying parallel with the side panels 20—20 and 45 adapted to be stitched thereto. The top of this divider 27 is slotted as at 29 to receive the side flaps 22 on the cover members.

I claim as my invention:

A shipping container comprising bottom, side 50 and end walls, the ends of the side walls being provided with integral flaps folded inwardly to substantially abut to form end walls, reinforcing flaps integral with said first-named flaps and folded back thereupon to reinforce the same, said 55

reinforced flaps substantially abutting except at the upper portions thereof and being spaced apart at their upper portions to form downwardly extending slots, the ends of the bottom wall being provided with integral flaps folded upwardly to overlap said reinforced flaps further to reinforce the end walls, said end walls having hand holds extending through the com-

bined thickness of the side wall flaps, the reinforcing flaps, and the upturned bottom wall end flaps, and cover members hinged to the side walls and having downturned side and end flanges, the side flanges being adapted to fit into the downwardly extending slots in the end walls when the cover members are closed. 5

ORVA O. NICKERSON.
